UNITED STATES PATENT OFFICE.

GEORGE F. A. OCHS, OF NEWARK, NEW JERSEY.

TRACK TOOL.

Application filed October 10, 1924. Serial No. 742,849.

To all whom it may concern:

Be it known that I, GEORGE F. A. OCHS, a citizen of the United States of America, residing at Newark, in the county of Essex and State of New Jersey, have invented new and useful Improvements in Track Tools, of which the following is a specification.

The purpose of the invention generally is to provide a tool for use in connection with the extraction and insertion of spikes for the attachment of the rails to the ties, and particularly as a means for inserting and extracting such spikes or holding elements as are disclosed in connection with the rail tie and fastening means of Patent No. 1,489,960, dated April 8, 1924.

A further purpose is to provide a construction adapted for raising the tie into contact with the rail base or depressing the latter into contact with the tie for the effective holding of the two in engagement during the spike inserting operation; to provide spike inserting and withdrawing elements actuatable independently; and to provide a construction of simple character and yet stable form so that it may be cheaply manufactured and yet effectively withstand the rough usage to which, in practice, it will be subjected.

With these purposes in view, the invention consists in a construction and combination of parts of which a preferred embodiment is illustrated in the accompanying drawings, wherein:

Figure 1 is an elevational view partly in section showing the invention applied in operative position for the extraction or insertion of a spike.

Figure 2 is a side elevational view of the structure of Figure 1, the tie being shown in section.

Figure 3 is a horizontal sectional view on the plane indicated by the line 3—3 of Figure 1.

Figure 4 is a vertical sectional view on the plane indicated by the line 4—4 of Figure 1.

The body 1, which is recessed on the lower end as indicated at 2 to provide a seat in which the ball or head 3 of the rail 4 may engage, is bored axially from the upper end and interiorly threaded to constitute a socket for the reception of the screw 5, the latter having a swivel mounting between the fixed collars 6 in a cross-head 7 and the screw being actuatable by means of a cross handle 8.

The cross-head supports the tie stirrups 9 which consist of downwardly divergent arms 10 terminally formed with inwardly facing hooks 11 for engagement with the under or bottom face of the tie 12. That the stirrups may be engaged with the tie, the arms of each stirrup are swingingly connected to the cross-head by means of studs 15 on the extremities of the latter engaging eyes in the stirrups at the connecting ends of the arms.

It is obvious from the construction just described that the rail base 16 and the tie 12 may be held firmly in engagement after the connection of the stirrups with the latter and the actuation of the screw 5 by the handle 6 to move the body 1 into firm engagement with the ball 3 of the rail.

The means for extracting and inserting the spikes 17 consist of independently operable elements of which one is disposed on each side of the body 1. The body 1 may be either a casting or forging and is formed on opposite sides with the brackets 18 having horizontal and vertical recess in which are disposed respectively the gears 19 and pinions 20. The gears 19 are provided with appropriate thrust bearings consisting of balls 21 disposed respectively above and below the gears, the balls traversing raceways formed in the upper and lower faces of the recesses, the upper raceway being accessible through openings 22 closed by removable screw plugs 23. The eyes of the gears 19 are threaded for the reception of the threaded shanks 24 of the spike pulling and inserting element, the spike claws 25 having a swivel connection 26 with the shanks and being provided with hinge elements 27 to permit the claws being swung away from and toward the spike, which movement, of course, is necessary in the initial engagement of a claw with a spike.

To elevate and lower the spike pulling and inserting elements, the pinions 20 are carried on stub shafts 28 journaled in the brackets 18 and exterior to the brackets are provided with the ratchet disk 29, the teeth of which are engageable with the pawls 30 pivotally mounted on studs 31 carried by the operating handle 32, the head 33 of the handle being engageable with the projecting extremity of the stub shaft for pivotal or swinging movement with reference to the latter. Thus, the oscillation of the handle will, through the pawl 30, cause intermittent

rotary movement in one direction to the stub shaft 28 and thereby effect rotation of the gear 19 with the consequent elevation or depression of the spike pulling or inserting element. The pawl 30, it will be noted, is reversible and depending on its position will depend whether such rotary movement communicated to the gear 19 is such as to elevate or depress the spike pulling or inserting element.

The head 33 may be disengaged from the stub shaft 28 merely by lateral movement in the direction of the stub shaft. Thus, it is readily attachable to either stub shaft and when in abutting engagement with the ratchet disk, the pawl is in position for engagement with the teeth of the ratchet disk.

The invention having been described, what is claimed as new and useful is:

1. A tool for the purpose indicated comprising a body element recessed at its lower end to provide a seat for the ball of a rail, a screw threadingly engaged with the body element at the end remote from the seat, a cross-head rotatably supported by the screw, and stirrups carried at the extremities of the cross-head and consisting of downwardly divergent arms formed with inwardly directed hooks for engagement with the bottom of a tie.

2. A tool for the purpose indicated comprising a body element recessed at its lower end to provide a seat for the ball of a rail, a screw threadingly engaged with the body element at the end remote from the seat, a cross-head rotatably supported by the screw, and stirrups carried at the extremities of the cross-head and consisting of downwardly divergent arms formed with inwardly directed hooks for engagement with the bottom of a tie, one of the arms of each stirrup being swingingly mounted with respect to the other.

3. A tool for the purpose indicated comprising a body element for engagement with the ball of a rail, stirrups carried by the body element for engagement with the under face of a tie, a spike extracting and inserting element carried by the body element, and means for imparting longitudinal movement to the spike extracting and inserting element.

4. A tool for the purpose indicated comprising a body element for engagement with the ball of a rail, stirrups carried by the body element for engagement with the un-

der face of a tie, a spike extracting and inserting element carried by the body element, and means for imparting longitudinal movement to the spike extracting and inserting element, the spike extracting and inserting element comprising a shank and a claw having a swivel connection with the shank at the lower end of the latter.

5. A tool for the purpose indicated comprising a body element for engagement with the ball of a rail, stirrups carried by the body element for engagement with the under face of a tie, a spike extracting and inserting element carried by the body element, and means for imparting longitudinal movement to the spike extracting and inserting element, the spike extracting and inserting element comprising a shank and a claw having a swivel connection with the shank at the lower end of the latter, and a hinge joint below the swivel connection.

6. A tool for the purpose indicated comprising a body element for engagement with the ball of a rail, stirrups connected with the body element and adapted for engagement with a tie, the body element being provided with a bracket, a gear couple carried by said bracket, a spike inserting and extracting element comprising a threaded shank engaged with the eye of one of the units of said gear couple, and an actuating handle operatively connected with the other of the units of said gear couple.

7. A tool for the purpose indicated comprising a body element for engagement with the ball of a rail, stirrups carried by the body element and adapted for engagement with a tie, the body element being provided with a bracket, a gear couple mounted in said bracket, one of the units of said couple having an internally threaded eye and the other of said units being provided with a stub shaft journaled in the bracket, a spike extracting and inserting element having a terminal claw for engagement with a spike, and a threaded shank engaged in the eye of the threaded unit of the gear couple, a ratchet disk carried by the stub shaft exteriorly to the bracket, an actuating handle having a head removably engaged with the extremity of the stub shaft, and a pawl engageable with the ratchet disk.

In testimony whereof I affix my signature.

GEORGE F. A. OCHS.
